CLAIM

The ornamental design for a computing device display screen or portion thereof with a graphical user interface, as shown and described.

DESCRIPTION

The FIGURE is a front view of a computing device display screen or portion thereof with a graphical user interface in accordance with the claimed design.

The outermost dot-dash broken lines showing the computing device display screen or portion thereof form no part of the claimed design. The remaining broken lines in the drawing show portions of the graphical user interface that do not form part of the claimed design.
